No. 763,776.

PATENTED JUNE 28, 1904.

J. MIDDAUGH,
WICK RAISER FOR LAMPS.
APPLICATION FILED OCT. 3 1903.

NO MODEL.

Fig. 1.

UNITED STATES PATENT OFFICE.

JAMES MIDDAUGH, OF DENNISON, OHIO, ASSIGNOR OF ONE-HALF TO
HENRY HESS, OF NEWCOMERSTOWN, OHIO.

WICK-RAISER FOR LAMPS.

SPECIFICATION forming part of Letters Patent No. 763,776, dated June 28, 1904.

Application filed October 3, 1903. Serial No. 175,667. (No model.)

To all whom it may concern:

Be it known that I, JAMES MIDDAUGH, a citizen of the United States, residing at Dennison, in the county of Tuscarawas and State of Ohio, 5 have invented new and useful Improvements in Wick-Raisers for Lamps, of which the following is a specification.

My invention has relation to new and useful improvements in wick-raisers for lamps, 10 and more especially to devices of that character or type as are employed in combination with the well-known forms of wick-raiser shafts for the purpose of operating said shaft to raise or lower the wick to regulate the flame.

15 The object of the invention is to provide a device of the character mentioned which is especially designed and constructed to be employed in connection with signal-lanterns of the form commonly employed by railway employees and other persons in outdoor signalling, when the lamp is more or less subject to the elements, and which will when operated serve to actuate the wick-raising shaft without the necessity of removing the chimney, 20 which exposes the flame to the wind and results in its being extinguished.

25 The invention consists in providing, in combination with a lamp-burner and its wick-raising shaft having a thumb-wheel, of a rotatably-mounted element carrying an engaging member which is adapted to be moved into engagement with the thumb-wheel to rotate the same, said element being provided with an operating device extending exterior to the 30 lamp casing or body, by means of which the element and engaging member are operated to raise or lower the wick.

35 I have fully and clearly illustrated my invention in the accompanying drawings, forming 40 a part of this specification, and wherein—

Figure 1 is a view in elevation of a signal-lantern of well-known construction in connection with which my invention is shown as being employed, a portion of the lamp-body, 45 wire guard, and chimney being broken away in order to better disclose the invention in its operative position. Fig. 2 is a detail perspective view of the invention detached from

operative relation to the lantern and its wick-raiser. 50

Referring to the drawings, 1 designates a base of a lantern comprising a circular concavo-convex plate provided with a vertical annular flange 2 of a suitable height, in which is seated and held by any suitable means a 55 cylindrical lamp body or casing 3, to the upper portions of which are secured the lower ends of the wires, as at 4, of which the chimney-guard 5 is constructed, the upper ends of said guard being secured to and supporting 60 the cap-piece or top 6 of the lantern. Supported upon the body 3 at the upper portion thereof is the lower end of the chimney 7, the upper end of which extends within the top or cap-piece, where it is held against displacement by any well-known means which will 65 efficiently accomplish the purpose.

Arranged within the lantern-body 3 and secured to the base 1 is an oil well or reservoir 70 of any suitable construction and is provided at its upper portion with a centrally-arranged burner 9, which is shown as being of that type employing a flat wick A, as is common in most signal-lanterns of the character shown. Extending transversely through the burner is the 75 usual rotatable wick-raiser shaft 10, carrying thereon within the burner suitable devices (not shown) for engaging the wick to raise or lower the same and is provided at its outer end with a thumb-wheel 11, by means of which 80 the shaft 10 is rotated, said wheel being provided with a serrated circumference, as at 12.

The lantern, as above described, and as shown in the drawings, forms no part of my invention, but is employed merely for the purpose of illustrating a signal-lantern of well-known construction in connection with which my invention is shown as applied in operative position with relation to the wick-raising means. It will be seen that in the lantern 85 above described the wick-raising means is located entirely within the chimney, which necessitates the removal of the chimney in order to gain access to the thumb-wheel when it is desired to adjust the wick, which exposes 90 the flame to the force of the wind and subjects 95

it to the liability of becoming extinguished. The attachment which I will now describe is devised for the purpose of providing for the adjustment of the wick from a point exterior 5 to the lamp without the necessity of removing the chimney or disturbing it in its ordinary position.

Rigidly mounted upon the oil reservoir or well 8 are upper and lower brackets 13 14, 10 provided at their end portions with vertically-arranged guides, shown as consisting of sleeves 15, which are spaced apart from each other and disposed in vertical alinement.

Rotatably arranged within the guides 15 and 15 longitudinally slideable therethrough in a vertical direction is a rod or element 16, the upper portion of which extends upwardly to a point a short distance above the thumb-wheel of the ordinary wick-raising means, where it 20 is provided with an inwardly-projecting arm 17, which when in normal position extends over the periphery of said wheel closely adjacent to the serrated edge thereof, but not in engagement therewith. The underside of the 25 arm 17 is formed with a sharp engaging face 18, which when the device is operated, as hereinafter described, is adapted to engage within one of the serrations formed in said wheel.

At its lower end portion below the guides 30 sleeves the element 16 is provided with a laterally-projecting operating device, which is shown as consisting of an arm 19, which is extended from within the lantern - body outwardly through an opening 20, formed in the 35 body and flange, so that the rod or element 16 may be operated from a point exterior to the burner and without detaching or moving any of the parts of the lantern from their normal or operative positions. By means of this 40 device 19 the element 16 may be either rotated in the guides or may be reciprocated therethrough, the slot 20 being of sufficient length and width as to permit the free movement of said device 19 in order to accomplish both 45 movements of the rod 16. It will be seen that by pressing the device 19 downwardly the engaging portions of the arm 17 will be moved into contact with the upper edge of the thumb-wheel 12 and that by swinging said device 50 either to the right or left the arm on the upper end of the rod 16 will be swung laterally to rotate the thumb-wheel to raise or lower the lamp-wick. As shown in the drawings, the engaging arm 17 and the operating device 55 19 are oppositely disposed with relation to the rod 16, so that a movement of the device 19 to the left moves the arm 17 in the opposite direction to operate the thumb-wheel.

For the purpose of holding the engaging 60 arm 17 normally out of position to engage the thumb-wheel, so as to prevent actuation of the wick-raiser owing to accidental move-

ment of the device 19, I provide a simple and effective means for maintaining the arm 17 a short distance above the thumb-wheel. This 65 means consists in providing the element 16 with an annular collar or projection 21, disposed in the space between the guide-sleeves 15. Arranged on the rod 16 is a spiral expansive spring 22, one end of which abuts 70 the collar 21 and the other of which rests against the lower guide 15, the functions of said spring being to force the rod 16 upwardly, the upward movement being limited by the collar 21 abutting the upper guide, as clearly 75 shown.

In order to operate the complete device as shown, the operating device 19 is moved to one side or the other of the slot 20, which movement swings the engaging arm 17 in an 80 opposite direction to take a position to one side of the vertical axis of the thumb-wheel. The device 9 is then moved downwardly, which pulls the rod 16 down in a longitudinal direction, so that the engaging face of the arm 17 85 is slightly below the upper surface of the thumb-wheel, when the device 19 is swung laterally, which rotates the rod 16 in the sleeves to throw the arms 17 into engagement with the periphery of the thumb-wheel, and 90 the continued movement of the rod will rotate said wheel to actuate the wick-raiser. If one movement of the rod 16 is not sufficient to adjust the wick to the desired degree, the device 19 is released, permitting the spring 95 22 to throw the rod upwardly and the arm 17 out of engagement with the thumb - wheel, when the rod is rotated to carry the arm 17 to its initial position, from which it may be again moved to turn the thumb-wheel. 100

Having thus described the invention, what I claim, and desire to secure by Letters Patent, is—

The combination with a lamp-body having vertically - disposed guides secured thereto 105 and one arranged over the other, a burner on the body having a rotary wick-raising means, a rod vertically slideable in the said guides and having an upper inturned angular end with a lower reduced edge to engage the wick-raising means and a lower outwardly-projected angular flattened foot, the rod also having a rotary movement in the guides, a spring surrounding the rods between the guides and connected at one terminal to said rod, and an enclosure for the said body having an elongated slot therein through which the flattened foot 115 at the lower end of the rod projects.

In testimony whereof I affix my signature in presence of two witnesses.

JAMES MIDDAUGH.
